UNITED STATES PATENT OFFICE.

JOHN F. COURSON, OF PITCAIRN, PENNSYLVANIA.

DRAFT-GEAR.

1,105,185.

Specification of Letters Patent.

Patented July 28, 1914.

Application filed January 6, 1914. Serial No. 810,583.

To all whom it may concern:

Be it known that I, JOHN F. COURSON, a citizen of the United States, residing at Pitcairn, in the county of Allegheny and State of Pennsylvania, have invented certain new and useful Improvements in Draft-Gears, of which the following is a specification.

My invention consists of an improvement 10 in draft gears for railway cars, etc., and has for its object to provide means, independent of the shock absorbing mechanism, which is usually combined to associate with the drawbar, means, independent of such 15 mechanism, for normally positioning the drawbar.

In draft gear apparatus of the friction or spring or other similar characteristic type, the drawbar is ordinarily returned to its 20 normal position by the resistance mechanism itself, after either buffing or pulling operations. Where springs are employed, either alone, or in combination with friction mechanism, return of the drawbar to its 25 normal position is frequently prevented or resisted, on account of the deterioration of the springs, binding of the friction mechanism, or other causes arising from continued use of the gear, wear, depreciation 30 of the parts, etc.

My invention has in view to provide mechanism operating directly upon the drawbar to return it to normal position when extended after pulling strains, de- 35 pressed after buffing strains, or when diverted laterally in either direction from normal central alignment.

The several above recited objects are accomplished by the construction illustrated 40 in the accompanying drawings, showing one preferred arrangement of the invention, in which—

Figure 1 is a central vertical partial sectional view of the complete draft gear assembled, the parts being in normal extended position, the section being indicated by the line I. I. of Fig. 2. Fig. 2 is a horizontal partial sectional view, indicated by the line II. II. of Fig. 1. Fig. 3 is a sectional view, 50 similar to Fig. 1, showing the drawbar extended, as in pulling, and showing the central wedge member forced backwardly. Fig. 4 is a transverse sectional view on the

line IV. IV. of Fig. 1. Figs. 5, 6 and 7 are perspective detail views of the separate 55 parts of the rocking centralizing member. Fig. 8 is a similar detail view of the supporting bracket for said member. Fig. 9 is a sectional detail view showing a modified construction.

In the drawings 2 represents the drawbar of the coupler fixedly connected with the wedge yoke 3 by a transverse key 4 extending through openings 5 in cheeks 6 of the wedge yoke 3 and through a suitable receiving opening in the rear portion of the drawbar, the key 4 being preferably held in position by cotters 7, or other suitable means. The wedge yoke 3 is provided at its rear portion with inner reversed wedge 65 faces 8, 8, co-acting with outer faces of wedges 9, 9, which in turn engage by their inner faces, the co-acting wedge faces of a central wedge 10.

Extending transversely through slots 11-75 at each side of the wedge yoke 3, is a follower 12 normally bearing by its terminals against the front stops 13, 13, of the central sills 14, for the transmission thereto of pulling strains.

The shock absorbing member D, which may be of any suitable construction, embodying spring gear or friction gear mechanism, or both, is mounted between the center sills 14 and bears backwardly by its 85 rear end against a resistance block or abutment 15, fixedly incorporated with or connected to the center sills 14 by rivets 16, or other suitable means. The abutment 15 is preferably provided with a forwardly extending ledge or bracket 17 for supporting the rear end of the shock absorbing member D, a supporting bracket 18 extending underneath its forward portion, and being secured to the center sills, as will be readily 90 understood.

The particular construction of the shock absorbing element or member D is immaterial to the operation of the gear, and may utilize friction-creating wedges 19, 19, having inner opposed wedge faces for engagement with the inner wedge terminal of wedge block 10, as shown, or the shock absorbing member may contain any suitable compressible resistance mechanism, against 100 which the rearwardly exerted force of ele- 105

ment 10 is exerted. In other words, the rear portion of the element 10 is not, *per se*, essentially wedge mechanism.

In operation, buffing strains effect rearward movement of drawbar 2, which are imparted through follower 12 to the front end of central wedge 10, these parts being normally in tight contact (as in Fig. 1), wedges 9 being merely carried backwardly 10 without action, and the rear end portion of element 10 exerting inward pressure to the coöperating contained portions of shock absorbing element D, the strains being eventually distributed to the car frame.

15 In pulling, follower 12, bearing against stop 13, resists forward travel of wedges 9, which are thus forced inwardly toward each other by wedge faces 8 of wedge yoke 3; thus converging upon the forward wedge 20 faces of member 10, thrusting it rearwardly, as shown in Fig. 3. By either buffing or pulling action, therefore, rearward movement is imparted to member 10 and to the shock absorbing element D. The shock absorbing construction above described may be substituted by any other suitable mechanism with which the drawbar may be connected. For the purpose of returning or assisting in returning the drawbar 2 to normal position, either when depressed or extended, or when deflected laterally in either direction, I provide between the under side of the drawbar and a supporting bracket 20, a rolling or rocking centralizing member seated in a circular dished cavity 21 at the upper inner central portion of the bracket 20. Said bracket, as shown in Fig. 8, may be made of a single metal piece having flanges 22 by which it may be bolted 30 or riveted to the lower flanges of the center sills 14, as shown, the dished cavity 21 being provided by an upper circular extension 35 23 from the bottom plate.

40 A central hole 24 provides clearance for a centralizing bolt 25, which extends through the central portion of bracket 20, centrally of the dished cavity 21, with an intervening rocking thimble 26. Said thimble, shown in detail in Fig. 7, is partly spherical, for 45 the purpose of providing a rolling bearing at the under side of the bracket, and coincident with the bolt hole 24.

The rocking centralizing member, in the particular construction illustrated, consists 50 of a rolling barrel or cylindrical body portion 27 having a partly spherical bottom 28, of a shorter radius than that of the bowl-shaped cavity 21, thereby providing for a rolling action thereon in any direction. The 55 rolling member 27 is provided at its upper portion with a pivotal supporting nose or lug 29, interfitting with a co-acting cavity 30, at the under side of the drawbar 2 and centrally thereof, as indicated in Fig. 2.

60 /The rolling member 27, as shown, is made

of two interfitting parts, the especial purpose of which is to facilitate the insertion of the bolt 25. Said bolt, in the construction shown, is provided with a surrounding coiled spring 31, which is compressed upon shifting of the member 27 from vertical position, in any direction. The spring thus assists in returning said member to its normal position, although the weight of the drawbar 2 is mainly depended upon for such 75 purposes. The spring 31 may therefore be dispensed with, if desired, although it is preferable to utilize the bolt 25 or its equivalent for centralizing the rocking member 27 upon its supporting bracket. 80

It will be seen that, upon movement of the drawbar in any direction, sufficient to exert a corresponding movement of the supporting rolling member 27, it will ride upwardly upon the concave annular bottom of cavity 85 21, and that the weight of the drawbar will ordinarily be exerted downwardly, at any maximum movement, or less movement, of the drawbar, within the periphery of cavity 21, as indicated by the lines *a*, *a*, and *b*, *b*, 90 (Fig. 3), showing the maximum movement at each side of the normal central line *c*, *c*. The drawbar will thus be returned to its normal position, largely by the exertion of the force of gravity, resulting from the weight 95 of the coupler itself and quite independent of any abnormal sticking or failure of the parts of the shock absorbing element D.

The degree of curvature of the bowl-shaped cavity 21 and of the bottom of the 100 rolling support, may be suitably designed to meet the conditions of service, construction, etc., and where the spring 31 is utilized, its strength may be varied for the same purpose. 105

In Fig. 9, I have shown a modified construction in which the position of the brackets 20' is reversed, being secured to the upper portion of the central car underframe with the concave surface of bowl-shaped 110 cavity 21' facing downwardly. In such case, the rocking member 27' is also reversed, its partly cylindrical surface 28' opposing the surface of the cavity 21', its other end being connected in any suitable manner with the 115 drawbar 2'. It will be understood that in such construction the drawbar is itself slidingly supported upon a lower bracket of suitable form, and that the rolling of the barrel element 27' against the concave under surface of the upper bearing effects a 120 separating tendency and resulting strain, with a corresponding tendency to roll toward the center, in the same manner as above described. 125

The construction and operation of the invention will be readily understood from the foregoing description. The centralizing element above described may be utilized with any available construction of draft gear or 130

drawbar, and, being entirely independent of the gear itself, is extremely useful and valuable in insuring return of the drawbar to normal position under the varying conditions of service.

Having described the invention, what I claim is:

1. The combination with a drawbar, shock absorbing mechanism associated therewith, and a bearing member, of a rocking centralizing device vertically opposed to the drawbar between it and said bearing member and embodying centralizing erecting means, co-acting with the drawbar and bearing member to support the drawbar at its varying positions and to return it to normal position.

2. The combination with a drawbar, shock absorbing mechanism associated therewith, and a bearing member, of a rocking centralizing device vertically opposed to the drawbar between it and said bearing member adapted to co-act with the drawbar and bearing member to support the drawbar at its varying positions, and provided with a centralizing bolt engaging the bearing member.

3. The combination with a drawbar and shock absorbing mechanism associated therewith, of a bearing member, and a rocking centralizing device embodying a spherical bearing surface co-acting with said bearing member at one end and having a pivotal bearing portion at the other end interposed between the drawbar and said bearing member for returning the drawbar to normal position.

4. The combination with a drawbar and shock absorbing mechanism associated there-

with, of a concaved bearing, and a rocking centralizing device interposed between the drawbar and said bearing and provided with a centralizing bolt connection therewith.

5. The combination with a drawbar and a concaved circular bearing member, of a rocking centralizing device having a spherically rounded bottom engaging said bearing and a pivotal terminal engaging the drawbar.

6. The combination with a drawbar and a concaved circular bearing member, of a rocking centralizing device having a rounded bottom engaging said bearing, a pivotal terminal engaging the drawbar, and a centralizing bolt connecting the centralizing device with said bearing member.

7. The combination with a drawbar and a concaved circular bearing member, of a rocking centralizing device having a rounded bottom engaging said bearing, a pivotal terminal engaging the drawbar, and a centralizing bolt connecting the centralizing device with said bearing member provided with a spring.

8. The combination with a drawbar and a bearing member, of a rocking centralizing device having a spherical-face engaging said bearing, a pivotal terminal engaging the drawbar, and a centralizing bolt connecting the centralizing device with said bearing member.

In testimony whereof I hereunto affix my signature in the presence of two witnesses.

JOHN F. COURSON.
